UNITED STATES PATENT OFFICE

167,998

HOSPITAL UTILITY STAND OR SIMILAR ARTICLE

Marie B. Raboli, San Mateo, Calif., assignor of one-half to Mills Memorial Hospital, San Mateo, Calif.

Application May 28, 1952, Serial No. 19,922

Term of patent 14 years

(Cl. D33—20)

To all whom it may concern:

Be it known that I, Marie B. Raboli, a citizen of the United States, residing at San Mateo, in the county of San Mateo and State of California, have invented a new, original, and ornamental Design for a Hospital Utility Stand or Similar Article, of which the following is a specification, reference being had to the accompanying drawing, forming part thereof.

Figure 1 is a perspective view of a hospital utility stand or similar article, showing my new design;

I claim:

The ornamental design for a hospital utility stand or similar article, as shown.

MARIE B. RABOLI.
